United States Patent Office

Des. 204,340
Patented Apr. 5, 1966

204,340

COMBINATION, DISPLAY, STORAGE AND DISPENSING CABINET

Thomas Andrew Carvel, Winding Road Farms,
Chauncey, N.Y.

Original application Apr. 28, 1964, Ser. No. 79,722, now
Design Patent No. 202,595, dated Oct. 19, 1965.
Divided and this application June 15, 1965, Ser. No.
86,214

Term of patent 14 years

(Cl. D80—2)

FIG. 1

FIG. 2

FIG. 1 is a front perspective view of a combination display, storage and dispensing cabinet, showing my new design.

FIG. 2 is a rear perspective view thereof.

This is a division of design application Serial Number D. 79,722, filed April 28, 1964, now Patent No. D. 202,595.

I claim:

The ornamental design for a combination display, storage and dispensing cabinet, as shown.
